UNITED STATES PATENT OFFICE.

FRANK S. HEBDEN, OF CHICAGO, ILLINOIS, ASSIGNOR OF ONE-HALF TO FRANCIS R. DENNIS, OF PEORIA, ILLINOIS.

SCALE.

1,237,332.

Specification of Letters Patent. Patented Aug. 21, 1917.

Application filed September 16, 1915. Serial No. 50,952.

To all whom it may concern:

Be it known that I, FRANK S. HEBDEN, a citizen of the United States, residing at Chicago, in the county of Cook and State 5 of Illinois, have invented certain new and useful Improvements in Scales, of which the following is a specification.

My invention relates to scales and especially to a scale adapted to weigh grain and 10 other substances while in transit or movement over a scale member.

My present invention is an improvement over my invention exhibited in Letters Patent No. 1,073,072, issued September 7, 1913, 15 and reference is made to said patent for announcement of the general principles and plan of operation of devices of this character.

My present invention has special reference to means of transmission from a driven carrying member of lateral movement occasioned by varying weights of materials being carried thereon; to special means for transmission of said movement to registering mechanism; to special means for supporting the carrying member, and to detail parts and combinations thereof hereinafter more particularly pointed out.

In the drawings—

30 Figure 1 is a plan view of my invention, a portion of the draper or carrying member being broken away to expose parts below;

Fig. 2 is a side elevation;

35 Fig. 3 is an end view, a portion of the draper or carrying member being broken away to expose interior parts;

40 Fig. 4 is a detail plan view showing a portion of the main draper carrying structure and the supplemental frame structure connected therewith, together with parts supported therein and showing a disk member in section;

Fig. 5 is a sectional view on line *a—a* of Fig. 4;

45 Fig. 6 is a detail view showing correlated disk members and means for supporting and guiding one of said members;

Fig. 7 is a sectional view of a compressible supporting member for draper belt;

50 Fig. 8 is a sectional view on the line *b—b* of Fig. 2 and

Fig. 9 is a detail view of correlated disk members, one of said members being broken away.

55 In carrying out my invention, I have

planned to properly support a traveling element, as for instance, a belt or draper in a manner adapted to receive the flow of grain or other material from a substantially continuous source of supply and to drive said belt from a suitable source of power, and to this end I have provided a rectangular base frame support 2, vertical standards 3 and 4, the latter supporting respectively roller members 5 and 6 fixed respectively 60 upon shafts 7 and 8, said roller members carrying a belt or draper member 9. I have illustrated in a diagrammatic manner a chute or spout 10 for the purpose of indicating a means of discharge from the supply 65 source of materials to the draper member 9. 11 is a belt wheel fixed to shaft 7 and is driven from belt 12. The upper reach of the draper member 9 is supported at its receiving end upon roller members 13, the latter 70 in turn supported upon standards 14 upon cross or connecting member 15, and at its outer end upon roller 16 supported upon standard 17. Intermediate the support of said draper member upon roller members 75 13 and 16, I have provided a compressible support, the latter comprising roller members 18 and 19 supported respectively in framing members 20 and 21. These members are in turn supported at their outer 80 ends respectively upon standards 22 and 23 by means of knife edge members 24 and 25 respectively upon said framing members 20 and 21, the same having bearing relation 85 in the concave seats 26 and 27 respectively of standards 22 and 23. The inner ends of members 20 and 21 are arranged to overlie 90 each other and are connected by link bar 28 in the manner shown, wherein the eye members of said bar engage with knife edge 95 members 29 and 30 respectively upon framing members 20 and 21. In this manner of support, assuming that the framing members 21 are held under yielding support, the material passing with the travel of draper 100 member 9 will cause said draper member to be compressed, and similarly the framing members 20 and 21 in varying degrees in conformity with weight of materials.

With a view of counterbalancing weight 105 for the belt member 9, I have provided the scale beam member 31 having the counterweight 32, said beam being supported in standards 33 through the knife engagement members 34 thereon engaging curved seats 110

in the upper ends of said standards 33. This scale beam member in practice is designed to be connected to support a cross frame member 35 of the main framing member 20, as best shown in Figs. 3 and 8. In order to compensate for and to facilitate the slight rocking motion of beam 31 to the frame member supported by it, I have provided the lugs 36 and 37 respectively upon 10 the beam member and the transverse frame member and the interposed block member 38. This manner of support serves, under proper counterbalancing, to cause any depression of the draper member below the 15 normal to be imparted to beam 31.

To the end of recording variations in weight of materials passing over the belt or draper member, I have in mind, as in the earlier application referred to, the idea 20 of utilizing relatively movable disk members as means to the end of registering such variations in weight, but have developed improvements on this feature of my invention which will be hereinafter more particularly pointed out.

Referring, then, to the means and associated mechanism serviceable for the purposes of imparting movement and registering variations in weight of materials passing 30 over the draper member, 39 is a shaft supported at one side in box 40 on framing member comprising uprights 41 and cross frame member 42. This shaft is supported at the opposite side of frame 2 in box member 43 on standard 44. Shaft 39 is connected to be driven from shaft 8 through sprocket wheel 45 on shaft 8 and sprocket wheel 46 on shaft 39, and sprocket chain 47 connecting said sprocket wheels. 48 is a concave disk 40 and 49 is a sleeve extension fixed to the end of shaft 39. 50 is a disk wheel supported in fork member 51 in a pivotal relation, said fork member being provided with the shaft or pin extension 52, said latter member being supported in bracket member 53, said bracket member being provided with shaft or pin extension 54 therefrom at right angles to the position of shaft or pin 52, and is supported in bearings in members 55, which 50 said members are supported from or form a part of framing arm 56 which said framing member is in turn connected and supported with framing member 57, said framing member 57 being bolted to the upper ends of 55 standards 41 as shown in Figs. 1 and 4. 58 is a cross framing member connected with or forming a part of frame 57 and is connected with or forms a part of standard 44 and is provided as an additional support 60 for said frame 57 to that of its connection with uprights 41. By means of the support of shaft 52 in bracket 53 and the support of said bracket from shaft 54 journaled in members 55, disk 50 is permitted to be 65 turned at an angle with relation to pivoting

pin member 54 and also to travel toward and from the central position with relation to disk 48. The turning center of disk 50 is adapted to be at the crossing point of pivoting pin or shaft members 52 and 54, 70 if member 54 were extended, and would also be the center of lines extended from concave disk member 48 on arcs conformatory with those of said disk. Disk 50 normally is designed in practice to be driven from contact 75 with traveling disk member 48 and to the end that such contact shall be constant, spring member 59 is provided, the same being carried upon shaft or pin member 52, and interposed between fork members 51 80 and the inner end of bracket 53.

I have provided means for changing the position of disk member 50 with relation to concave disk 48 with the depression of draper member 9 and resultant movement of beam 31. The particular means employed for this purpose comprises a shaft member 60 having trunnion extensions 61, which said shaft is journaled at one end in the bearings comprising rollers 62 and at the other end in boxing member 63 which is secured at the inner end of framing member 64, the latter being fixed to the frame 57. To the shaft is secured a weight member 65 by means of reach 66, said reach being connected respectively with shaft 60 and weight 65. This weight serves to maintain the shaft in normal position. To shaft 60 is attached in a rigid manner the arm 67, and to said arm is connected in a pivotal manner link member 68, the lower end thereof being provided with the yoke 69 which supports ring members 70, said ring members serving as a support or connection with beam 31 through the knife edge members 71 projecting from either side of said beam. This connection of shaft 60 with beam 31 serves to convey the movement of said beam to the sleeve, serving to rock the latter upon its support 61. To the inner end of shaft 60 there is fixed the arm 72 provided at its outer end with the open slotted way 73 best shown in Fig. 6. To one of the fork members 51 is fixed the reach 75 extending parallel with disk 50 to the outer edge thereof, and then inturned, and then extended for the purpose of alining the outer portion of said reach with the edge of said disk. The outer end of reach 75 extends within the slotted way in arm 72. Disk 50 is normally placed slightly off center of disk 48, that is, the bearing of disk 50 is a little to one side of the center of the axis of support for said disk 48, this for a purpose to be explained. Arm 72 is positioned to hold disk 50 in its normal position slightly off center with relation to disk 48 and as beam 31 is moved downwardly, disk 50 will be rocked slightly toward the circumference of disk 48 and hence the movement of said disk 48 will cause disk 50 to travel toward 110 115 120 125 130

the circumference of disk 48 and similarly, when beam 31 rises, disk 50 will be turned to travel toward the center of disk 48. In this manner of connection between arm 72 and the fork members 51 which support disk 50, there is no bodily movement of disk 50 upon the surface of disk 48, as in my former patent herein referred to, and hence the friction clutch is dispensed with, said disk 10 traveling and moving forwardly in such change of position relative to disk 48. The movement or change of position of disk 50 with relation to the surface of disk 48 changes both the distances between arm 72 15 and said disk 50 and also the angular disposition of reach 75 with relation to slotted way 73 in said arm, which said differing in relative positioning is readily taken care of by the said slotted way. The action of these 20 parts is best seen in Fig. 6.

The speed of movement of disk 50 is adapted to be registered or measured, and to this end a proper meter or register 76 is provided which may be of any suitable construction, to serve the purpose. Register 76 is supported upon plate member 77 and is adapted to be driven by connection with an axial spindle 74 of said disk 50 through coil spring member or flexible shaft 79. Disk member 50 is normally placed slightly removed from the axial center of disk 48 as actual centering of these members would render them inoperative, since the movement of disk 50 is dependent for travel on 25 contact and angular positioning with reference to disk 48. Therefore disk 50 must be off center with relation to disk 48 to receive any impetus from the latter. As a consequence of the relative placement of disk 50 30 off center from disk 48, disk 50 would run at all times regardless of whether materials were passing upon the draper belt. Hence it is necessary to compensate for such movement, and to this end I have provided a 35 planetary gear mechanism 80 (not illustrated or described in detail as it is a gear of well known type and forms no part of my present invention). I also provide a connection for driving this gear comprising 40 sprocket wheel 81 on shaft 39, gear wheel 82 on shaft 83, the latter supported on bracket members 84, sprocket wheel 85 also on shaft 83, sprocket wheel 86 connected with sleeve member 87 of the planetary gear organization, and suitable sprocket chain driving 45 connections between the sprocket wheels mentioned. The effect of the interposition of the planetary gear and driving connection therefor is to exactly counterbalance the 50 driving speed resulting in a normal placement of disk 50 when the machine is running but the traveling draper carrying no materials. However, as disk wheel 50 moves from its normal position toward the circumference of disk 48, movement will be im-

parted to the registering mechanism to properly measure the distance traveled by said disk.

In operation, the parts of the device having been disposed in the related positions shown and power having been applied to operate the traveling members, including the draper belt and disk member 48, grain or other materials passing to the draper belt will be passed over the compressible members of the frame, causing the latter to be depressed and therewith the scale member, which depression of the scale member, through its connection with disk 50, will cause the latter to be turned more or less, as the weight is greater or less. With the turning of the disk 50, the travel of disk 48 will cause said disk 50 to be moved toward the circumference of disk 48, thus increasing the speed of the former in proportion as the distance increases from the axial center of disk 48. The diminishing weight will be marked by inclining the disk toward the axial center, resulting in its traveling in that direction. A sudden discontinuance of weight upon the traveling member and the compressible members will be automatically taken care of through and by a positioning weight 65 on sleeve 60. The travel of disk 50 will be transferred through its connection with the registering mechanism as hereinbefore described.

What I claim is:

1. In a device of the class described, in combination, a support, a compressible member therein, a traveling member in said support having bearing relation with the compressible member therein, means for driving the traveling member, a scale beam operatively connected with said compressible member in a relation to be actuated thereby, a concaved disk member, means for actuating the same in conjunction with the traveling member, a second disk member adapted to be actuated by the first named disk member, means for shifting the second named disk to different angular positions with relation to the first named disk operable through the movement of the scale beam.

2. In a device of the class described, in combination, a support, a compressible member therein, a traveling member in said support having bearing relation with said compressible member in a relation to be actuated thereby, a concaved disk, means for actuating said disk in conjunction with the traveling member, a second disk disposed at right angles with the surface of the first named disk and rotatable from the movement of the latter, means operable through the movement of the scale member to shifting said disk to different angular positions with reference to the axis and circumference of the first named disk, and means connecting the axis of the second named disk with suitable

registering mechanism that the travel of the latter disk may be registered.

3. In a device of the class described, in combination, a support, a depressible member therein, a traveling member movable on said support and having a bearing relation with the depressible member thereof, and capable of being depressed under the weight of materials being carried upon said traveling member, means for driving the traveling member, a scale member operatively connected with said depressible member in a relation to be actuated by the latter, a rotatable disk member, means for actuating the latter in conjunction with the traveling member, a second disk member suitably supported for rotation in peripheral contact with the surface of the first named disk, means actuated by the scale member for changing to different angular positions of the second named disk with relation to the axis and circumference of the first named disk, means for registering the travel of the second named disk.

25 4. In a device of the class described, in combination, a support, a depressible member therein, a traveling member movable on said support and having a bearing relation with the depressible member thereof, and capable of being depressed under the weight of materials being carried upon said traveling member, means for driving the traveling member, a scale member operatively connected with said depressible member in a relation to be actuated by the latter, a rotatable disk member, means for actuating the latter in conjunction with the traveling member, a second disk member suitably supported for rotation in peripheral yielding contact with the surface of the first named disk, means actuated by the scale member for changing to different angular positions of the second named disk with relation to the axis and circumference of the first named disk, means for registering the travel of the second named disk.

5. In a device of the class described, in combination, a support, a depressible member therein, a traveling member movable on said support and having a bearing relation with the depressible member thereof, and capable of being depressed under the weight of materials being carried upon said traveling member, means for driving the traveling member, a scale member operatively connected with said depressible member in a relation to be actuated by the latter, a rotatable disk member, means for actuating the latter in conjunction with the traveling member, a second disk member suitably supported for rotation in peripheral yielding contact with the surface of the first named disk, means actuated by the scale member for changing the position of the second named disk with relation to the axis and circumfer-

ence of the first named disk, comprising a rockable member, an eccentrically related connection between the rockable member and the scale member, an arm on the rockable member and a connection between said arm and the second named disk, and means for registering the travel of the second named disk.

6. In a device of the class described, in combination, a support, a depressible member therein, a traveling member movable on said support and having a bearing relation with the depressible member thereof, and capable of being depressed under the weight of materials being carried upon said traveling member, means for driving the traveling member, a scale member operatively connected with said depressible member in a relation to be actuated by the latter, a rotatable disk member, means for actuating the latter in conjunction with the traveling member, a second disk member suitably supported for rotation in peripheral yielding contact with the surface of the first named disk, means actuated by the scale member for changing the position of the second named disk with relation to the axis and circumference of the first named disk, comprising a rockable member, an eccentrically related connection between the rockable member and the scale member, an arm on the rockable member and a loose, extensible connection between the said arm and the second named disk, and means for registering the travel of the second named disk.

7. In a device of the class described, in combination, a frame, a depressible member therein, a traveling member capable of yielding and imparting its movement to the depressible member under the weight of the load carried thereon, means for driving the traveling member, a disk member, means for driving the latter in conjunction with the traveling member, a second disk member associated for peripheral contact with the surface of the first named disk, and rotatable with the movement of the latter, means for supporting the second disk member to permit it to be turned to rotate about a center at right angles with its axis of support, and also laterally with relation to the circumference and center of said first named disk, a scale member operably connected with said depressible member in a relation to be actuated thereby, means for moving the second named disk to different positions between the axial center and circumference of the first named disk, operable through the movement of the scale member, and means operably connecting the second named disk with the registering means that travel of the former may be registered.

8. In a device of the class described, a supporting frame, a depressible member therein, a traveling member thereon capable

- of being depressed to actuate the depressible member through the weight of materials carried by said traveling member, means for driving the traveling member, a scale beam 5 supporting the depressible member normally in balance, a disk, means for rotating the disk in conjunction with the traveling member, a second disk member adapted to be actuated for rotation by the first named 10 disk, means actuated by the movement of the scale member for shifting, guiding and supporting the second disk member in different angular positions relative to the axial center and circumference of the first named 15 disk, means for registering the movement of the second disk member, and driving connections between the said second disk member and the registering means.
9. In a device of the class described, a 20 supporting frame, a depressible member therein, a traveling member thereon capable of being depressed to actuate the depressible member through the weight of materials carried by said traveling member, means for driving the traveling member, a scale member supporting the depressible member normally in balance, a concave disk member, means for rotating same in conjunction with the traveling member, a 25 second disk member adapted to be actuated for rotation by the first named disk, means actuated by the movement of the scale member for guiding and supporting the second disk member in different positions relative 30 to the axial center and circumference of the first named disk, means for registering the movement of the second disk member, and driving connections between the said second disk member and the registering means.
10. In a device of the class described, in 35 combination, a supporting frame, provided with a carrying surface including depressible members, a traveling draper member carried upon said supporting members depressible under the weight of materials carried thereon, means for driving the traveling member, a scale member supporting the depressible members of the frame in normal balance, a concave rotatable disk, means for 40 rotating the disk in conformity with the movement of the draper member, a second disk positioned at right angles with relation to the line of movement of the first named disk, means for supporting the second 45 named disk in yielding contact relation with the first named disk for permitting said second named disk to be turned at different angles to its axis of support, and to be moved bodily throughout portions of an arc conformatory with that described by the 50 concave face of the first named disk, means for turning said second named disk and for directing its travel to different positions upon said first named disk actuated by the movement of the scale member, suitable registering means and connections therefrom with said second named disk to facilitate the proper measuring of the travel of the latter. 55
11. In a device of the class described, in combination, a bearing support for the traveling member thereon including depressible members, a scale member supporting the depressible members of the frame in normal balance, a traveling member having a bearing relation with said support, means for 60 driving the traveling member, a disk member, means for driving said disk in conformity with the movement of said traveling member, a second disk disposed at right angles to the axial center of said first named 65 disk and at one side from said center, and suitably supported to be driven from the first named disk, means actuated by the scale member causing the second named disk to be positioned at different points relative to the 70 axial center and circumference of the first named disk, a registering mechanism and connections for actuating the same from the second named disk, and means for neutralizing the action of said driving connection 75 between the second named disk and the registering mechanism to compensate for the movement of said disk in its normal position when no materials are being carried upon the traveling member. 80
12. In a device of the class described, in combination, a support, a depressible member therein, a traveling member having a bearing relation with the depressible member therein, means for driving the traveling 85 member, a scale beam operatively connected with said depressible member in a relation to be actuated thereby, a concave disk member, means for actuating the same in conjunction with the traveling member, a second disk member adapted to be actuated by the first named disk member disposed off center with relation to the axis of the first disk member, means for shifting the second named disk to different positions relative to 90 the axial center and circumference of the first named disk operable through the movement of the scale beam. 95
